SIGNALING SYSTEM FOR RAILROADS

Oscar S. Field, Rochester, N. Y., assignor to General Railway Signal Company, Rochester, N. Y.

Application September 26, 1933, Serial No. 691,026

1 Claim. (Cl. 246—34)

This invention relates to signaling systems for railroads, and more particularly to means by which a train, the axles of which are electrically insulated from the running rail, can manifest its presence in a particular section of track in such a system.

The conventional steam railway train effects a dependable electrical shunt upon a railway signaling track circuit including the steel rails of such a track by the various steel wheels and axles which are held in good current conducting contact with such rails by the comparatively great weight of the cars. However, certain railway cars having non-conducting wheels or running 10 on non-conducting rails or treads cannot manifest their presence in the various sections of track by effecting a shunt on such a railway signaling track circuit.

In view of the above and other considerations, it is proposed in accordance with the present invention to provide on a railway car a means other than the conventional wheels and axles for effectively shunting the metallic car carrying rails of a railway signaling track circuit, and if the car carrying rails or treads are not of a conducting material, it is further proposed to provide auxiliary conductors along the trackway which operate with the above mentioned shunting means. It is also proposed to superimpose 20 carried energy upon such shunting means to thereby check the integrity and the sufficiency of such shunt according to the resistance offered to the flow of such car-carried current, and it is further proposed to superimpose such energy in a manner which does not interfere with the sensitivity of a conventionally arranged track circuit.

Other objects, purposes and characteristic features of the present invention will appear as the description thereof progresses, during which, references will be made to the accompanying single figure of drawing which shows in a diagrammatic and conventional manner a railway signaling track circuit and a car-carried shunting means therefor arranged in accordance with the present invention.

Referring to the drawing, a railway car is diagrammatically shown by a dotted figure C as occupying a conventionally arranged insulated track section including a source of energy E connected across one end of the parallel rails or conductors 2 and 3 with a conventional track relay TR connected across the other ends. These conductors 2 and 3 may be the car-carrying rails if such are metallic or current conducting, or in

applications employing non-conducting rails or treads, they may be auxiliary insulated conductors suitably supported along the trackway.

The railway car C is provided with two pairs of shunt shoes or brushes, RS¹ and RS² bearing on the right hand rail 3, and LS¹ and LS² bearing on the left hand rail 2. These shunt shoes or brushes are insulated from each other and from the body of the car C, and the car-carried apparatus associated with these rail shunting shoes includes a closed core electrical choke CH and a power supply transformer T. Shunt indicating relays IR and IL are also associated with the rear shunt shoes and are connected into the shunting means by the associated 10 transformers RT and LT and an associated 15 full wave rectifier FR and FL.

The above described apparatus at the rear of the car C associated with the shunt shoes RS¹, RS², LS¹ and LS² is duplicated at the forward 20 end of the car and is connected in an identical manner to the similar shunt shoes or brushes RS³, RS⁴, LS³ and LS⁴. For the purpose of simplifying the present disclosure, the forward 25 apparatus will be considered to be identical to the rear apparatus and consequently like reference characters have been assigned thereto with distinctive exponents. It may be here mentioned that the duplicate apparatus located on the forward and rear ends of the car has been shown 30 both for the purpose of providing a more reliable shunt while the car occupies an intermediate position in the track section as well as for retaining such shunt while the car is standing or passing 35 over the insulated joints between two track sections, which insulated joints may be staggered or spaced longitudinally such a distance that the right hand shunt shoes associated with only one of the two shunting means shown bears on a conductor of one track section and left hand shoes 40 associated with the same shunting means bears on the opposite conductor of the adjacent track section thereby shunting neither of the adjacent sections if two spaced duplicate shunting means 45 were not provided.

An alternator A is provided on the car C for continuously supplying a suitable frequency of alternating current to both the rear transformer T and the forward transformer T¹. It is contemplated that this alternator A may be driven 50 by any suitable means such as the means employed for propelling the car C.

It is believed now that the usefulness and the various inter-related functions of the device and the circuits of this specific embodiment of the 55

present invention will be more readily understood by further description being given from the standpoint of operation.

The track section shown in the accompanying drawing is of the conventional closed circuit type which obviously maintains the relay TR energized when the section of the rails 2 and 3 included therein is not occupied by the car C, but as shown in the accompanying drawing, the energy from the source E is shunted through the various multiple paths completed by the car-carried shunt shoes to effect the dropping of the armature of relay TR. For example, one path for the shunted current may be traced from the rail 2 through the shunt shoes LS² through the low resistance primary 4 of the transformer LT, wire 5, through the low resistance secondary winding 6 of transformer T, through a second low resistance secondary winding 8 of the transformer T, through the low resistance winding 9 of transformer RT, wire 10 and to the opposite rail 3 through the shunt shoe RS². The shunt shoes LS¹ and RS¹ also furnish a shunt path for the direct current from the source of energy E which may be traced from the rail 2 through the shunt shoe LS¹, wire 11, through the low resistance winding 12 of the closed core choke CH, wires 13 and 14, through a second low resistance winding 15 on the choke CH, wire 16 and to the opposite rail 3 through the shunt shoe RS¹.

The secondary windings of the transformer T and the primary windings of transformers LT and RT are to be of comparatively heavy wire as well as their interconnecting leads in order to afford a low resistance path for this shunt circuit, and likewise the coils 12 and 15 of the choke CH are to be of very low resistance and to have low resistance interconnecting wires for the same reason. The source of energy E for the track circuit is preferably of a type such as a storage battery for supplying direct current to the rails 2 and 3 in order that the shunt paths including the windings of the various transformers and the windings of the choke CH will impede the flow of such current only due to their resistance which is very small as previously stated, or in other words, the inductance or capacitance of these shunt circuits will in no way impede the flow of continuous current from the track circuit battery E.

The previously traced shunt paths effected by the shunt shoes LS¹, LS², RS¹ and RS² are obviously in multiple with similar paths through the apparatus provided at the forward end of the car C, or effected by the shunt shoes LS³, LS⁴, RS³ and RS⁴, but because of their similarity it is not considered necessary to trace the circuits in detail.

The alternating current supplied to the primary of transformer T is induced into the secondary windings 6 and 8 for the purpose of checking the integrity of the contact between the rear shunt shoes and the rails 2 and 3. The circuit for this alternating current induced in a secondary winding 8 of transformer T may be traced from the upper terminal of winding 8, wires 7 and 14, through winding 15 of the choke CH, wire 16, shunt shoe RS¹, through rail 3, shunt shoe RS², wire 10 and through the primary winding 9 of transformer RT to the opposite terminal of the secondary winding 8. The alternating current thus flowing through the primary of transformer RT induces a current in a secondary winding 24 which is changed to direct current by the full wave rectifier FR to maintain the direct current

indicating relay IR energized. The energization of relay IR energizes an indicating light R over an obvious circuit completed by front contact 28 to display an indication that the shunt shoes RS¹ and RS² are effecting a sufficiently low resistance contact with the rail 3 to afford a shunt on the track relay TR.

The integrity of the contact between the left hand shunt shoes LS¹ and LS² and the rail 2 is also checked by a similar circuit energized by 10 the secondary winding 6 of transformer T, which circuit may be traced from the upper terminal of the secondary winding 6, wires 7 and 13, winding 12 of the choke CH wire 11, shunt shoe LS¹, through the rail 2, shunt shoe LS², primary winding 4 of transformer LT and back to the opposite terminal of the secondary winding 6 by wire 5. In like manner, the alternating current flowing in the above circuit energizes the relay IL by the transformer LT and the full wave rectifier FL to energize lamp L at front contact 20 and thereby indicate the sufficiency of the contact between the left hand shunt shoes and the rail 2.

The secondaries of transformers T and T¹ are 25 so arranged that the upper terminals of the secondary windings 6 and 18 and the lower terminals of the secondary windings 8 and 19 are all of the same instantaneous polarity, or in transformer T, the windings 6 and 8 being relatively 30 oppositely arranged, it is obvious that current will flow in wires 13 and 14 in the same instantaneous direction. Also, the windings 12 and 15 of the choke CH are so arranged that equal and opposite instantaneous values of flux are 35 produced thereby in the closed core of the choke CH. These equal and opposite values of flux obviously result in a negligible flow of flux within the core of the choke CH thereby producing a negligible amount of reactance to the flow of 40 alternating current in the windings 12 and 15.

In a similar manner, the integrity of the contact between the shunt shoes of the forward duplicate shunting means and their associated conductors is checked by alternating current from 45 the associated transformer T¹, or a secondary winding 19 of the transformer T¹ normally causes current to flow through the shunt shoes RS³ and RS⁴ in series to maintain the relay IR¹ energized thereby lighting the associated indicating light R¹. Also, current is supplied to the left hand forward shunt shoes LS³ and LS⁴ in series by a secondary winding 18 of the transformer T¹, and in a similar manner is effective to normally energize the relay IL¹ and indicate the sufficiency 55 of the contact of these shunt shoes by energizing the indicating light L¹.

It will now be evident that if some abnormal condition increases the resistance between any pair of shunt shoes and the associated rail above 60 a value which is predetermined for effecting a reliable shunt upon the track relay TR, the value of the alternating current flowing in series with such a pair of shunt shoes will be sufficiently reduced to effect the dropping of the associated indicating relay, thereby indicating such an abnormal condition by extinguishing the indicating light controlled thereby. In addition to this releasing of the relay associated with the defective contact shoe, the reduction of current in the 65 choke winding in series with the defective shunt shoe will allow flux produced by the opposing choke winding to flow within the core of the choke and thereby produce an impedance in the opposite checking circuit which sufficiently re- 75

duces the alternating current therein to also release the indicating relay associated with the opposite shunt shoes. For example, the failure of either shunt shoe RS^1 or RS^2 obviously reduces the checking current to release relay IR , but this reduction of current in choke winding 15 unbalances the flux in the core of the choke CH and allows its winding 12 to act as an impedance which reduces the current flowing through the shunt shoes LS^1 and LS^2 to a point which also releases relay IL and energizes the indicating light L .

In regard to the function of the response of both indicating means to the failure of one side of the shunting means only, it is contemplated that a single indicating means may suffice for each of the duplicated shunting arrangements. In other words, a single indicating light may be jointly controlled by both relays or the complete apparatus associated with one indicator such as L may be omitted with a suitable impedance inserted in place of the transformer LT .

As previously described, the normal flow of alternating current through the coils of the choke CH produces opposing flux to result in a negligible impedance, but when the shunting means is duplicated for the front and rear of the car, a valuable function of these chokes is to prevent the flow of alternating current from one of the duplicated shunting means to the other in case of a failure of one or more of the shunt shoes to effect a low resistance contact with its rail. Or that is, if the chokes CH and CH^1 were not provided, sufficient current might obtain during the failure of a shunt shoe due to alternating current flowing between the duplicate shunting means to falsely indicate a shunt across the rails.

For example, in the event of the failure of either shunt shoe RS^1 or LS^4 or both, an abnormal path for the car-carried alternating current may then be formed from the upper terminal of the transformer secondary 8 , wire 7 and 13 , choke winding 12 , wire 11 , shunt shoes LS^1 , rail 2 , shunt shoe LS^3 , primary winding 39 of transformer LT^1 , wire 29 , transformer secondary 18 , wires 24 and 25 , choke winding 26 , wire 27 , shunt shoe RS^4 , rail 3 , shunt shoe RS^2 , wire 10 , primary winding 9 to transformer RT and back to the lower terminal of secondary winding 8 . Inasmuch as the upper terminal of transformer secondary 8 is of a relatively opposite instantaneous polarity to the upper terminal of transformer secondary 18 , it will be obvious that the voltage thereof will be additive, or each tending to cause current to flow in the same instantaneous direction in the above traced abnormal circuit.

However, the closed core chokes CH and CH^1 function in the above traced abnormal circuit to impede the flow of alternating current to an extent that sufficient current is not supplied by transformer RT to hold up relay IR in case shunt shoe RS^1 has failed and likewise sufficient current is not supplied by transformer LT^1 to relay IL in case shunt shoe LS^4 has failed. In other words the failure of the shunt shoe RS^1 obviously de-energizes winding 15 of the choke CH which allows flux produced by the abnormal current in winding 12 to flow within the core of the choke CH and thereby limit the flow of alternating current due to the impedance of the choke winding 12 to a value which will not maintain either relay IL energized by its normal circuit or relay IR energized over the above abnormal circuit. In a very similar manner the failure of the shunt shoe LS^4 will de-energize winding 22 of choke CH^1 and

allow the impedance of winding 26 to limit the flow of alternating current to a value effecting the release of both relays IL^1 and IR^1 .

Likewise, in case of the failure of either shunt shoe LS^1 or RS^4 or both the choke windings 15 and 22 function in the same manner to limit the flow of alternating current in a similar abnormal circuit thus formed. It will be obvious also that in case of the failure of either shunt shoes RS^2 , LS^2 , RS^3 or LS^3 , an abnormal circuit cannot be formed which will include the associated indicating transformers and consequently such a failure will be indicated directly.

A car-carried means for effecting the shunting of a direct current track circuit has thus been provided in which provision has been made for checking the integrity of the contact between the car and the trackway conductors or rails in order that an indication may always be obtained of the sufficiency of the car-carried means to shunt such a direct current track circuit. Attention is particularly directed to the means by which the sufficiency of the contact between the car and the trackway conductors is checked, which comprises a means for superimposing a car-carried source of alternating current upon the shunt circuit in a manner to check the integrity of the contact between the car and the conductors and yet which does not in any way effect the sensitivity of the conventional track circuit. In other words, the present invention has disclosed a means whereby the current employed for checking the integrity of the shunt is permitted to flow through brushes or shunt shoes in series which bear upon one of the track circuit conductors only instead of applying such car-carried energy in multiple with the source of energy for the track circuit, in which latter case it is obvious that a pulsating current would be produced in the track relay which would materially reduce its sensitivity.

In addition to the feature of checking the sufficiency of the contact between the car and the trackway conductors in accordance with the amount of car-carried current flowing between the car and the trackway conductors, this flow of alternating current has the further advantage of breaking down a high resistance film which is found to ordinarily exist between these brushes and the trackway conductors, and it is contemplated that this breaking down of such film will materially decrease the resistance of the shunt circuit to the flow of the direct current track circuit energy.

In the embodiment shown, the indicating relays are employed to control an indicating light which gives a visible indication concerning the integrity of the associated shunt shoes, but it is obvious that these relays may be arranged to give any desirable indication either visible or audible, and it is further contemplated that such relays may be employed to control the application of an auxiliary shunting means. An auxiliary shunting means which the above mentioned indicating relays may control is fully shown and described in the application of W. K. Howe, Ser. No. 645,013, filed November 30, 1933.

It is also to be understood that in the disclosure of the present invention the shunting apparatus has been duplicated at the forward and rear ends of the car for the various purposes described, but it is contemplated that this duplication may be considered unnecessary in some applications. In such applications employing only one of the duplicated shunting means shown, it is to be understood that the closed core chokes with coils in

each of the checking circuits may then be omitted. The above rather specific description of one form of the present invention is given solely by the way of example, and is not intended in any manner whatsoever in a limiting sense. It is also to be understood that various modifications, adaptations and alterations may be applied to meet the requirements of practice, without in any manner, departing from the spirit or scope of the present invention except as limited by the appended claim.

Having thus described my invention, what I claim is:

In combination with a railway vehicle out of electrical contact with its metallic running rails, two spaced pairs of insulated conductors carried by the vehicle and in contact with one rail, two other spaced pairs of insulated conductors carried by the vehicle and in contact with the other

5 rail, means causing rail resistance break-down alternating current to flow along a track rail from one to the other of the two conductors of each of the four pairs of conductors in a given direction at any given instant, means interconnecting like 5 potential points of each of the two pairs contacting with the one rail, each to an opposite pair of the two pairs contacting with the other rail, thus constituting two spaced interconnected pairs, an electrical choke for each of the two interconnected pairs, each choke comprising a core, two windings on the core and each connected in series with two conductors constituting a pair, the windings being positioned on the core to produce opposing magnetomotive forces when they are 15 traversed by the alternating current flowing in said given direction, and means for indicating the flow of current in each pair of conductors.

OSCAR S. FIELD.
